UNITED STATES PATENT OFFICE.

GEORGE T. MOORE, OF NEW YORK, N. Y.

SASH-CHAIN.

SPECIFICATION forming part of Letters Patent No. 357,620, dated February 15, 1887.

Application filed November 11, 1886. Serial No. 218,514. (No model.)

To all whom it may concern:

Be it known that I, GEORGE T. MOORE, a citizen of the United States, residing at New York, in the county of New York and State of New York, have invented certain new and useful Improvements in Sash-Chains and Plumbers' Chains, of which the following is a specification, reference being had therein to the accompanying drawings.

10 This invention relates to certain new and useful improvements in chains formed by links cut from sheet metal, having special reference to what are known in the trade as "sash" and "plumbers'" chains; and the object of the invention is to strengthen that portion of the links which lies between the slots formed in the ends of the links, so as to prevent said portion from breaking when the chain is undergoing extreme tensile strain, 15 the tendency of which is to draw out or flatten the bent portion of the links, and to thus make the bend too acute to withstand breakage.

15 In the accompanying drawings, forming a part of this specification, and on which similar letters of reference indicate the same or corresponding features, Figure 1 represents a plan view of a chain composed of several of my improved links. Fig. 2 is an edge view thereof; Fig. 3, a view of a link before it is folded, and Fig. 4 a cross-sectional view of the portion between the slots.

20 The common way of manufacturing chain-links of the character to which my improvement relates is by stamping the links from sheet metal by means of a die, the stamp also cutting the slots in the ends of the link-blank. This same method is followed in manufacturing my improved link, so far as concerns the features of it which are now well known.

25 Referring now to the accompanying drawings, the letter A designates the links stamped from sheet metal, with slots B and an intermediate imperforated portion, C. After stamping, (or during the operation of stamping, if the die be so constructed,) the said intermediate por-

tion is formed with a depression on one side and a corresponding bulge on the opposite side, forming a groove, and a bead upon the respective sides. A link thus made is bent or folded over, and then a number of links are 50 strung together to form a chain.

It will be observed that the portion which receives the bend presents, substantially, a semicircle, which is the natural curvature the metal takes in folding the link, and which 55 curvature does not disturb the molecules sufficiently to expose the curved portion to breakage or to cracking on the outer side. When, however, excessive strain is brought upon the chain, the curved portion without my improved bead tends to draw out or flatten, which action cracks the outside of the bend and causes the link to break. With the bead in the bent portion, however, this flattening action, due to excessive strain, is successfully resisted, 60 and hence the tensile strength of the chain is multiplied many-fold.

It should be noted that while this improvement confers the benefits named upon the chain, it does not materially increase the cost 7c of manufacture, nor does it involve a greater consumption of material.

Having thus fully described my invention, what I claim as new, and desire to secure by Letters Patent, is—

1. A sheet-metal chain-link having the central curved portion thereof provided with a depression on one side and a bulge on the other, produced by swaging the metal thereof.

2. A sheet-metal chain-link provided with 80 a slot near each end and with an intermediate imperforated bent portion provided with a depression on one side and a bulge on the other.

In testimony whereof I affix my signature in presence of two witnesses.

GEORGE T. MOORE.
